(57) **CLAIM**

The ornamental design for a retainer for eyeglasses as shown and described.

DESCRIPTION

FIG. 1 is a perspective view of the retainer for eyeglasses in a straight configuration;

FIG. 2 is a right side view thereof;

FIG. 3 is a left side view thereof;

FIG. 4 is a bottom side view thereof;

FIG. 5 is a top side view thereof;

FIG. 6 is a front end view thereof;

FIG. 7 is a rear end view thereof;

FIG. 8 is a perspective view of two of the retainers attached to glasses.

FIG. 9 is a perspective view of the retainer for eyeglasses in a curved configuration;

FIG. 10 is a right side view thereof;

FIG. 11 is a left side view thereof;

FIG. 12 is a bottom side view thereof;

FIG. 13 is a top side view thereof;

FIG. 14 is a front end view thereof; and,

FIG. 15 is a rear end view thereof.

The broken lines in FIGS. 7 and 14 show portions of the article and form no part of the claimed design. The broken lines in FIG. 8 show environmental subject matter and form no part of the claimed design.
